UNITED STATES PATENT OFFICE.

BERTHOLD HUBER AND WILLIS K. HODGMAN, OF TAUNTON, MASSACHUSETTS.

INKING APPARATUS FOR PRINTING-MACHINES.

SPECIFICATION forming part of Letters Patent No. 368,339, dated August 16, 1887.

Application filed September 2, 1886. Serial No. 212,561. (No model.)

To all whom it may concern:

Be it known that we, BERTHOLD HUBER and WILLIS K. HODGMAN, both of the city of Taunton, in the county of Bristol and State of Massachusetts, have invented certain Improvements in Inking Apparatus for Printing-Machines, of which the following is a specification.

Our invention relates to that class of printing-presses known as the "bed-and-cylinder press," in which the form reciprocates under the impression-cylinder.

The form is supplied with ink before each impression by means of "form-rollers," one or more of which (termed a "set") are arranged on one side of the impression-cylinder, so that the form as it reciprocates will pass back and forth under the same in contact therewith. As the rollers receive a fresh supply of ink for each impression, it is evident that the end of the form which first comes in contact therewith will take therefrom the greatest quantity of ink, and that the rollers will deposit less and less ink as they approach the opposite end of the form, whereby the latter is unevenly inked.

The object of our invention is to remedy this defect and obtain a more equal distribution of the ink upon the form.

To this end our invention consists in the combinations of mechanism hereinafter more particularly set forth and claimed.

Figure 1 is an elevation of a printing-press embodying our invention. Fig. 2 is a vertical section of the same. Fig. 3 shows position of the movable set of form-rollers when raised clear of the form.

Similar letters refer to similar parts throughout the several views.

The side frames, A, together with the cross-stays A', constitute the principal frame-work of the machine.

The impression-cylinder C makes two turns during one complete stroke of the bed, which latter carries the form B. The movement of the impression-cylinder and bed is similar to any two-revolution press, and motion can be given to them in any well-known manner. The two form-rollers R, together with their rider or distributer roller D, constitute one set, the form-rollers R being driven by friction with

the rider-roller D, which is driven by a spur-gear on one end, which meshes with the intermediate gear, G⁵. The intermediate gear, G⁵, is driven by a second intermediate gear, (shown in dotted lines,) which meshes with a third intermediate gear, (shown in dotted lines,) which latter is driven by the form-roller driving-gear G⁴, which is fastened to one end of the shaft S³ outside of the side frame, A. Motion 6~ is given to the shaft S³ by means of the pulley P, secured thereon just inside of the side frame, A. The driving-belt P² passes over the pulley P, and also over the loose pulley P', which runs on the stud S⁴, the ends being fastened to the bed. The two form-rollers R', together with their rider-roller D', constitute a set. The said rollers R' D' are journaled in the two roller-stands C⁶, and are driven by the same means employed to drive 70 the form-rollers R and the rider-roller D. The two roller-stands C⁶ rest on the side frames, A, and are fulcrumed on the stay-rod S², which is secured between the two fly-stands F². The free ends of the two roller-stands C⁶ admit of 75 being raised enough to clear the form-rollers R' from the form B as it comes from beneath the impression-cylinder C, but not sufficiently to disconnect the gear on the end of the rider-roller D' from the intermediate gear, G⁵. The 80 free ends of the roller-stands C⁶ are raised and lowered at the proper time by the trip-cam C', which is secured to the shaft S.

Motion is transmitted to the roller-stands C⁶ by means of the cam-roller R², connecting-rod C², lever C', shaft S', two levers, C⁴, and two connecting-rods, C⁵. The cam-shaft S is caused to rotate by the train of spur-gears, which are driven by the cylinder-gear G, consisting of the gears G¹ G², a pinion on the hub of G², 90 (not shown,) and G³.

The feed-board and fly are lettered, respectively, F and F'.

Ink is supplied to the ink-table I from the fountain-roller I² by means of the usual ductor-roller I¹, and is distributed thereon by the rollers I'.

In Figs. 1 and 2 we have shown the press about to make an impression, and the bed is on its forward or printing stroke.

In the positions shown in Figs. 1 and 2 the end of the form B nearest the impression-cyl-

inder C is at the head of the form, and the end most remote from the cylinder C is at the tail.

Operation: The operation and construction of a press embodying our invention are similar to an ordinary bed-and-cylinder press, excepting the operation and effect of the set of rollers composed of the two form-rollers R' and their rider-roller D', which, by means of the mechanism described, are lowered into contact with the form B during the printing or forward stroke of the bed, and raised out of contact with said form B while the latter is passing under the form-rollers R' during the back-stroke of the bed. The set of rollers composed of the two form-rollers R and their rider-roller D always retain the same relative position to the surface of the form B, and therefore come in contact therewith during both strokes of the bed. As the bed reciprocates forward and back the form B is rolled from both directions by the two form-rollers R, the most ink, however, being applied to its tail end, which comes in contact with the rollers R just after they have left the ink-table I, and are therefore freshly charged with ink. The two form-rollers R', by not coming in contact with the form B during the back-stroke of the bed, apply the most ink, commencing at the head end of the form, thus equalizing and improving the distribution of ink over the entire form. In Fig. 3 we have shown the position of the movable set of rollers when raised clear of the form B during the back-stroke of the bed.

Having fully described our invention, what we claim as new, and desire to secure by Letters Patent, is—

1. An impression cylinder, a reciprocating form-carrier, and two sets of form-rollers with their rider-rollers, the said rider-rollers having each a gear-pinion fixed thereto, one set of form-rollers and rider-roller journaled in

fixed bearings and the other set journaled in movable bearings, combined with a gear-wheel, as g⁶, suitably supported in fixed position and 45 positively driven through immediate connecting mechanism by the motor which reciprocates the form-carrier, the said gear-wheel being arranged intermediate of the rider-rollers and continuously meshing with the gear-pins 50 on said rider-rollers, and mechanism, substantially as described, to raise or elevate the set of rollers which are journaled in the movable bearings during the back-stroke of the reciprocating bed or form-carrier, as and for 55 the purpose set forth.

2. The pivoted roller-stands C⁰, with the rollers R' R' D' journaled in the free end thereof, the roller D' having a pinion fixed thereto, which continuously meshes with the fixed 60 positively-driven gear-wheel G⁵, combined with said gear-wheel G⁶, the cam-roller R², connecting-rod C², levers C³ C⁴, shaft S', rods C⁵, and rotating cam-shaft S, and the form, inking-table, and set of fixed form-rollers and 65 rider-roller, substantially as set forth.

3. The set of form and rider rollers journaled in fixed bearings, and a roller stand or bracket pivoted at one end and provided at its other end with a set of form and rider rollers 70 journaled therein, substantially as specified, combined with means, substantially as described, to raise or elevate the said roller-stand on its pivot, and with a positively-driven gear-wheel intermediate of the rider-rollers 75 of the two sets of rollers and continuously meshing with pinions secured to said rider-rollers, as and for the purpose set forth.
